HOWARD D. MATTHEWS, OF EDGEWOOD, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed January 16, 1924. Serial No. 686,691.

My invention relates to electrical protective devices and particularly to thermal relays.

One object of my invention is to provide a thermal relay that shall have such a time interval in the operation thereof as to afford protection to electrical apparatus against continued overloads.

Another object of my invention is to provide a thermal relay, of the cartridge type and of the above-indicated character, that shall have means whereby its contact members are quickly actuated in both the opening and closing operations under predetermined conditions.

A further object of my invention is to provide a thermal relay, of the above-indicated character, that shall be compact in form, relatively inexpensive to construct and reliable and effective in its operation.

My invention comprises, in general, an enclosed cylindrical casing with connecting ferrules at the ends thereof. A base member that is operatively connected between the ferrules supports a bimetallic member and an insulated terminal member. The terminal member supports a resilient contact member that is adapted to engage a movable contact member under predetermined conditions.

The movable contact member is so mounted as to be actuated with a snap action either toward or away from the resilient contact member by the bimetallic member co-operating with a system of springs. The movable contact member is surrounded by an insulating bushing that is so mounted as to preclude engagement of the two contact members when the movable contact member moves to one end of its path of movement.

In the accompanying drawings:

Figure 1 is a side view, partially in elevation and partially in section, of a thermal relay embodying my invention.

Fig. 2 is a view, partially in plan and partially in section, of the relay shown in Fig. 1.

Fig. 3 is a sectional end view of the same relay.

Fig. 4 is a diagrammatic view of electric circuits in which the relay embodying my invention may be used; and

Fig. 5 is a side view, partially in elevation and partially in section, of an alternative method of mounting the movable contact member in the relay embodying my invention, and

Fig. 6 is a partial sectional view taken on the line VI—VI of Fig. 1.

Referring to Figs. 1, 2 and 3 of the drawing, a cylindrical casing 1 supports a ferrule 2 at one end and a ferrule 3 at the other end thereof. A base member 4 is rigidly secured to the ferrule 3 and supports a bimetallic member 5 by means of a screw 5^a and an insulating bushing 5^b. The base member 4 and the bimetallic member 5 are further supported by a bracket member 6 that is rigidly secured to the ferrule 2.

The base member 4 supports a terminal member 7 by means of a screw 7^a, but is electrically insulated therefrom. One end of the terminal member 7 extends through an insulating bushing 8 in the ferrule 2 and supports a terminal screw 9. The other end of the terminal member supports a resilient contact member 10 that is biased toward the base member 4 and engages a movable contact member 11 when the free end of the bimetallic member 5 is relatively close to the base member 4.

The contact member 11 is attached to one end of a pin 12 that is slidably mounted in an enclosing metallic bushing 13. The bushing 13 is adjustably mounted on an extending member 14 that is rigidly fastened to the free end of the bimetallic member 5. The end of the pin 12 that is opposite to the end supporting the contact member 11 is provided with a groove 15 for receiving one end of each of the flat springs 16 and 17. The opposite ends of these springs engage slots in a pair of supporting members 18 and 19, respectively, that are rigidly mounted on the base member 4.

A longitudinal slot 20 extending from one end thereof divides the bimetallic member 5 into two parts 21 and 22. The part 22 is electrically connected to the bracket member 6 but is insulated from the base member 4 by an insulating member 23. The part 21 is similarly connected to the base member 4 and insulated from the bracket member 6 by an insulating plate 23^a (see Fig. 6).

Thus a circuit is established from the fer- and the pin 25 and, consequently, the bushing 27 are thereby actuated in the same direction. rule 2 to the ferrule 3 through the bracket member 6, parts 22 and 21, respectively, of the bimetallic member 5, and the base member 4. When sufficient current traverses this circuit to heat the bimetallic member above a predetermined degree, its free end is moved away from the base member 4. The extending member 14 that is attached to the free end of the bimetallic member 5, thereby actuates the bushing 13 in the same direction and an annular shoulder 24 on the pin 12 causes this pin and the contact member 11 that is supported thereby, to be also moved in the same direction.

If the current traversing the bimetallic member 5 is sufficient to cause the pin 12 to be actuated, in the manner described, until the groove 15 comes into line with the slots 20 in the supporting members 18 and 19, the resultant force exerted by the springs 16 and 17 on the pin 12 parallel to the axis thereof becomes zero, and any further actuation of the pin 12 in the same direction 25 causes the springs 16 and 17 to tend to rapidly continue the actuation of the pin 12 in this direction.

The pin 12 is so mounted with respect to the bushing 13 as to permit it to move freely 30 in this direction over a certain distance. This distance is limited by a pin 25 that extends through the bushing 13 and a slot 26 in the pin 12. When the pin 12 has moved to such position that the bottom of 35 the slot 26 engages the pin 25, further actuation of the pin with respect to the bushing 13 is precluded.

An insulating bushing 27 is so mounted on the metallic bushing 13 by the pin 25 that 40 its lower edge engages the resilient contact member 10 before the pin 12 has reached the end of its path of free movement with respect to the bushing 13. The resilient contact member 10 is so biased that it tends 45 to remain in engagement with the movable contact member 11 as the pin 12 and the contact member 11 are actuated by the bimetallic member 5 in the manner described. When it is engaged by the lower edge of the insulating bushing 27, however, further movement 50 of this member in this direction is precluded, and it is rapidly disengaged by the contact member 11 by reason of the quick actuation of the pin 12 by the springs 16 and 17.

The relay embodying my invention is 55 adapted to be so connected in an electrical system that disengagement of the contact members 10 and 11 causes the circuit extending through the bimetallic member 5 to be interrupted. When this circuit is interrupted, the temperature of this member decreases and the free end of the bimetallic member moves toward its original position adjacent to the base member 4. The extending member 14, the bushings 13 and 27,

The pin 25, engaging the bottom of the slot 26, causes the pin 12 and the contact member 11 to be also actuated in the same direction. When the pin 12 has moved so that the resultant force exerted thereon by the springs 16 and 17 tends to rapidly continue its movement in the same direction, the pin 12 and contact member 11 are given such a snap action by the springs that the contact member 11 quickly engages the contact member 10. The circuits controlled by the relay are such that when these contact members are re-engaged, the circuit extending through the bimetallic member 5 is again completed and the apparatus is in condition for operation in the same manner as previously described.

Referring to Fig. 4 of the drawings, an electrical translating apparatus 28, to be protected, is adapted to be supplied with energy from a source 29 through a relay 30, embodying my invention, and a circuit interrupter 31. When the contact members 10 and 11 of the relay are in engagement, a circuit is completed extending from the source 29 through the ferrule 3, base member 4, supporting members 18 and 19, springs 16 and 17, pin 12, contact members 11 and 10, terminal member 7 and low-voltage trip coil 32 of the circuit interrupter 31, to the opposite terminal of the source 29. The coil 32 is thereby energized from the source 29 and so attracts an armature member 33 as to hold the movable member of the circuit interrupter 31 in its circuit-closing position, as shown in the diagram, through the toggle mechanism 34.

With the circuit interrupter 31 in its circuit-closing position, energy is supplied to the apparatus 28 from the source 29 through the relay 30 and the circuit interrupter 31. The circuit through the relay 30 traversed by this energy extends from the ferrule 3 through the base member 4, the parts 21 and 22, respectively, of the bimetallic member 5, and the bracket member 6 to the ferrule 2.

When the current traversing this circuit exceeds a predetermined value during a predetermined interval of time, the contact members 10 and 11 are disengaged, as previously described, to interrupt the circuit extending through the trip coil 32 of the circuit interrupter 31. When this coil is thus de-energized, the armature member 33 drops to permit a compression spring 35 to act upon the toggle mechanism 34 in such manner as to cause the circuit interrupter 31 to interrupt the circuit extending to the apparatus 28.

When the contact members 10 and 11 are re-engaged, because of the cooling of the bimetallic member 5, the circuit through the

trip coil is re-established to hold the circuit interrupter 31 closed after it has been returned to its circuit-closing condition. The system is now in the same condition as previously described and the relay 30 is in condition to again interrupt the circuit extending through the apparatus 28 should this circuit be traversed by a current in excess of the predetermined value over the predetermined interval of time.

Operation of this relay under any desired conditions within its range may be obtained by properly adjusting the position of the threaded bushing 13 with respect to the extending member 14.

Figure 5 of the drawing shows an alternative construction for the contact mechanism of the relay embodying my invention. The free end of the bimetallic member 5 supports an extending member 14 similar to that described for the preferred form of my invention. A pin 36 is adjustably mounted on the extending member 14 and is adapted to actuate a relatively movable member 37 that is rigidly attached to the pin 12. The springs 16 and 17 are mounted as before between the supporting members 18 and 19 and the pin 12. The bimetallic member 5 now actuates the pin 12 through the extending member 14, the pin 36 and the member 37 until the springs 16 and 17 co-operate to give the pin 12 a snap action in a direction away from the resilient contact member 10. When this action takes place, engagement of the contact members 10 and 11 is precluded because the lower end of the pin 36 engages an insulating member 38 that is mounted on the resilient member 10.

Re-engagement of the contact members 10 and 11 in this form of my invention is effected by the actuation of the pin 12 toward the resilient member 10 from the bimetallic member 5 through the extending member 14, the pin 36 and the member 37. This form of relay embodying my invention may be adjusted to operate under any desired conditions within its range by adjusting the position of the threaded pin 36 with respect to the extending member 14.

My invention is not limited to the applications illustrated nor to the structure of the relay as described above, as various modifications may be made therein, and it may be adapted to protect various devices without departing from the spirit and scope of the invention, as set forth in the appended claims.

I claim as my invention:

1. A thermal relay for electrical apparatus comprising a bimetallic member, one end of which is freely movable through a definite path, a relatively movable contact member supported by the bimetallic member, a resiliently mounted contact member which remains in engagement with the first contact

member during a certain part of its movement, and means whereby engagement of the two contact members is positively precluded when the first contact member is actuated with a snap action.

2. A thermal relay for electrical apparatus comprising a bimetallic member, one end of which is freely movable through a definite path, a relatively movable contact member supported by the bimetallic member, a second contact member so resiliently mounted that it remains in engagement with the first contact member during a certain part of its movement, and an insulating member so mounted on said second contact member as to positively preclude engagement of the two contact members when the first contact member has traversed a certain part of its path of movement.

3. A thermal relay for electrical apparatus comprising a bimetallic member, one end of which is freely movable through a definite path, and which supports a relatively adjustable bushing enclosing a relatively movable pin, and spring means whereby the pin is given a snap action when it is forced beyond a certain point in its path of movement by the adjustable bushing.

4. A thermal relay for electrical apparatus comprising a bimetallic member, one end of which is freely movable through a definite path, a pin, and spring means co-operating with the bimetallic member to actuate the pin with a snap action in either of two directions when the bimetallic member reaches certain points in its path of movement, corresponding to definite predetermined temperatures of the bimetallic member.

5. A thermal relay for electrical apparatus comprising a bimetallic member, an adjustable bushing, a coaxial pin, and spring means co-operating with the bimetallic member to actuate the pin with a snap action in either of two directions, when the free end of the bimetallic member reaches certain points on its path of free movement, corresponding to predetermined temperatures of the bimetallic member.

6. A thermal relay for electrical apparatus comprising a bimetallic member, one end of which is freely movable through a definite path, a relatively adjustable bushing, a relatively movable coaxial pin supporting a contact member, a resiliently mounted contact member, and spring means co-operating with the bimetallic member to cause the two contact members to disengage rapidly under predetermined conditions.

7. A thermal relay for electrical apparatus comprising a bimetallic member, one end of which is freely movable through a definite path, a relatively adjustable bushing, a relatively movable coaxial pin supporting a contact member, a resiliently

mounted contact member, and spring means co-operating with the bimetallic member to cause the two contact members to engage rapidly under predetermined conditions.

8. A thermal relay for electrical apparatus comprising a bimetallic member, one end of which is freely movable through a definite path, a relatively adjustable bushing, a relatively movable coaxial pin supporting a contact member, a resiliently mounted contact member, and a plurality of co-operating flat springs that have a path of motion extending through a plane in which the resultant force exerted by the springs on the movable pin is zero, and that are adapted to co-operate with the bimetallic member

to cause the contact members to rapidly engage or disengage under predetermined conditions.

9. A thermal relay for electrical apparatus comprising a bimetallic member, a stationary contact member, a second contact member supported by the bimetallic member, a toggle-spring mechanism, and means whereby the bimetallic member controls the spring mechanism to actuate the contact members rapidly into and out of engagement.

In testimony whereof, I have hereunto subscribed my name this 8th day of January, 1924.

HOWARD D. MATTHEWS.
